(57) **CLAIM**

The ornamental design for a drawstring tool, as shown.

DESCRIPTION

FIG. 1 is a perspective view of a drawstring tool showing our new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a front elevational view thereof; and,

FIG. 7 is a rear elevational view thereof.

The broken lines illustrating a loop in FIG. 1 are directed to environment and form no part of the claim.
